ATTORNEY

UNITED STATES PATENT OFFICE.

MATTHIAS C. USINGER, OF PHILADELPHIA, PENNSYLVANIA.

TABLE-PAD.

1,333,884.

Specification of Letters Patent. Patented Mar. 16, 1920.

Application filed April 11, 1918. Serial No. 227,864.

To all whom it may concern:

Be it known that I, MATTHIAS C. USINGER, a citizen of the United States, residing in the city and county of Philadelphia, State 5 of Pennsylvania, have invented certain new and useful Improvements in Table-Pads, of which the following is a specification.

My invention relates to a pad or the like for tables or other articles of furniture, and 10 particularly for dining room tables, for the purpose of preventing transmission of heat from hot dishes to the table, and in general for protecting the table top.

My invention relates to structure of the 15 character referred to in which single backed corrugated board or air cell board is provided on the side opposite the single backing with a cloth or other soft and very flexible backing which presents a smooth, soft 20 surface to the finish of a table top, operates to a certain extent as a silencer, and provides a structure which as a whole may readily be rolled up into small volume for shipping or packing, or for storage when 25 not in use upon a table.

My invention resides in the structure hereinabove described and claimed.

For an illustration of one of the various 30 forms my invention may take, reference is to be had to the accompanying drawing, in which:

Figure 1 is a sectional view of a pad embodying my invention.

Fig. 2 shows the structure in a suitable 35 position for application of the cloth or soft flexible backing.

Fig. 3 is a sectional view illustrating the 40 pad structure rolled up into small space.

Fig. 4 is a top plan view of a pad structure made up of several parts corresponding to table parts and inserted leaves.

Referring to the drawing, 1 represents 45 corrugated paper board, as jute tag board, to which is applied, as by adhesive, the single backing 2 of paper or the like, as jute tag board, asbestos paper or board and the like, the combination of the parts 1 and 2 being well known as single backed air cell or corrugated board. On the side of the 50 corrugated member 1 opposite to the backing 2 is a backing 3 of cloth, such as outing flannel, or other similar soft yielding and very flexible material.

The material 3 is preferably applied by 55 adhesive to the corrugated member 1 when

the latter is bent or disposed in convex position as indicated in Fig. 2, in which case the material 3 is applied to the longer or outer side of the convex formation of the material 1. This insures when the structure is again 60 flattened that the backing 3 has a fullness which increases its padding effect; but of greater importance is the fact that the fullness is such that the pad structure as a whole may be readily rolled up in close formation as indicated in Fig. 3, as for packing or shipping, or for storage when the pad structure is not in use upon a table. This 65 fullness of the material 3 affords additional flexibility to permit rolling of the pad as 70 indicated in Fig. 3, the material 3 being on the inside of the roll, as shown. It will be understood, however, that my invention is not limited to the fullness of material 3 produced as above described. The material 3 75 may also be applied with the pad structure as a whole substantially flat, in which case it may also be rolled up with the material 3 on the inside of the roll.

The backing 2 may also be of material 80 other than that hereinbefore described; for example, it may be of a moisture-proof material such as oilcloth. By preference, however, such an extra layer of moisture-proofing material, as oilcloth, is applied on the 85 paper backing 2 as indicated at 4.

In use the cloth 4 is placed against the table top, the sheet 4 forming the upper surface of the pad.

It will be understood that the pad structure described may be of any shape or size. It may be formed in small units for individual dishes, or it may cover the entire table top, as indicated in Fig. 4, in which case there are 4 pieces, the pieces 5, 5 corresponding with the top sections of the table proper, while the leaves 6, 6 correspond with inserted table leaves.

In such structure it will be understood that each of the parts 5 and 6 is separately 100 rollable into close compact form as indicated in Fig. 3.

What I claim is:

1. A flexible, rollable table pad comprising a corrugated member having a flexible 105 backing, secured on one side of said member, a flexible cloth backing attached to the corrugations on the other side of said member, said cloth backing having a length between neighboring crests of said corrugated 110

member greater than the distance between said neighboring crests, and a moisture proofing sheet on said first-named backing.

2. A table pad comprising a corrugated member, a backing on one side of said member, and a flexible cloth backing attached to the corrugations on the other side of said member, said cloth backing having a length between neighboring crests of said corrugated

member greater than the distance between said neighboring crests, whereby the pad may be rolled with said cloth backing on the inside. 10

In testimony whereof I have hereunto affixed my signature this 10th day of April, 1918.

MATTHIAS C. USINGER.
